(57) **CLAIM**

I claim the ornamental design for a display screen of a network device with graphical user interface, as shown and described.

DESCRIPTION

FIG. 1 is a first image of a display screen with an animated graphical user interface; and, FIG. 2 is the second image thereof.

The appearance of the transitional image sequentially transitions between the images shown in FIGS. 1-2. The process or period in which one image transitions to another image forms no part of the claimed design.
